UNITED STATES PATENT OFFICE.

ROBERT L. COONEY, OF ATLANTA, GEORGIA.

PRESSURE-CONTROLLED FIRE-EXTINGUISHER SYSTEM.

1,075,283.

Specification of Letters Patent.

Patented Oct. 7, 1913.

Application filed January 28, 1910, Serial No. 540,661. Renewed August 23, 1913. Serial No. 780,347.

To all whom it may concern:

Be it known that I, ROBERT L. COONEY, a citizen of the United States, residing at Atlanta, in the county of Fulton and State 5 of Georgia, have invented new and useful Improvements in Pressure-Controlled Fire-Extinguisher Systems, of which the following is a specification.

This invention relates to new and useful 10 improvements in pressure controlled fire extinguisher systems.

The type of pressure controlled system to which the present improvement relates is one wherein two bodies of elastic fluid 15 are normally maintained at equal or balanced degrees of pressure in such a relation that one body, the "dominant" body, is subject to reduction or retraction consequent to the opening of a sprinkler head, 20 distributing valve or equivalent device and the other body, the "servient" body (which is normally held in restraint by the "dominant" body) becomes active, (i. e. expands) as a consequence of the reduction or 25 retraction of the "dominant" body to cause, by expansion or projection, the operation of a fire extinguisher agent supply means.

The invention embodies an improved apparatus for maintaining the proper relation 30 of the pressures and for carrying out the steps of operation stated in the foregoing paragraph.

The purpose of the present arrangement is to provide for a positive, infallible and 35 practically instantaneous operation with an apparatus which requires but a low degree of charging pressure and which is extremely simple in construction.

Embodiments of the invention are dis- 40 closed in the accompanying drawings, wherein—

Figure 1 is a sectional view of an apparatus in accordance with the present invention. Fig. 2 is a similar view of an alterna- 45 tive form of apparatus. Fig. 3 is a sec- tional view of an alternative structural detail.

Similar characters of reference refer to corresponding parts in the two views.

The apparatus shown is of the chemical mixing type and the chemical mixing means 50 is contained in a tank or shell, as 1. Because of this characteristic of containing the fire extinguishing agent supply means, the tank or shell 1 is arbitrarily termed the "primary" tank, the word "primary" in

this connection being used to signify a tank in which the operation of the means for supplying the fire extinguishing agent takes place. A shell 2 is operatively related to 60 the primary shell, being preferably set into an end head thereof. The shell 2 is essentially an elastic fluid container and for this reason is arbitrarily termed the "secondary" shell, the word "secondary" in this 65 connection being used to signify a shell, which, without regard to any other characteristics that it may have in a particular embodiment, is essentially an elastic fluid container.

The system supply pipe, hereinafter termed the "distributing" pipe, is designated by the numeral 3 and is connected to the shell 2.

Any means or arrangement of means for 75 putting elastic fluid under pressure in the tanks, and in the distributing pipe may be employed. A carboy, as 4, is shown as an example of such a means. This carboy is charged with compressed air, or a gas fatal 80 to combustion, and may be conveniently connected to the distributing pipe 3 by a connection 5. This arrangement admits of interposing in the connection 5 certain adjunctive devices tending to promote the 85 efficiency of the system, e. g., a pressure reducer, as 6, which maintains the pressure at some determined absolute degree, a pressure indicator, as 7, and a safety valve, as 8, for relieving excess pressure due to over-gener- 90 ation in the case of a chemical mixing sys- tem.

The shell 2 rests upon a ledge, as 9, which is formed at one end of the shell 1 in the upper portion thereof, and said shell is 95 provided with a reduced barrel, as 11, which projects into the shell 1 and which has an extension, as 10, which projects into the shell 2 and is concentric therewith. The barrel 11 is provided with a pipe section, 100 as 12, which extends to a point near the bottom of the shell 1 and which serves as the outlet pipe for the fire extinguishing solution, the latter passing first through the section 12, then through the shell 2 and then 105 into the supply pipe 3 by which it is distributed by the system.

The chemical mixing action may be pro- 110 duced by overturning an acid bottle, as 13, whereby its contents will mix with a body of alkaline solution which partially fills the tank 1. The acid bottle 13 is pivotally

supported off and below center, brackets, as 14, being provided for this purpose. The preferred means for causing the overturning movement of the acid bottle consists of a plunger, as 15, which is slideable axially of the shell 2, and which is so related to the acid bottle that the overturning of the latter is consequent to an operative axial movement of the plunger. The operative connections between the plunger and the acid bottle include a rod, as 16, which projects axially of the barrel 10 through an opening 17 in the end thereof, and a chain, as 18, which connects the rod 16 and a cap, as 19, that forms the closure of the acid bottle, being fitted loosely over the upper end thereof.

The plunger 15 is provided with an aperture, as 20, which provides for the flow of the pressure vehicle from the shell 2 to the shell 1, when the system is charged, but which does not allow the pressure in the shell 1 to flow into the shell 2 to any material extent when the pressure in the latter is suddenly and materially reduced consequent to the opening of a sprinkler head or equivalent device. The aperture 20 does, however, provide for the equalization of the pressure in the shells 1 and 2 in the event of leakage, and consequently, the pressures are always balanced, irrespective of their absolute degree.

In operation, when a sprinkler head or equivalent device is opened, the pressure in the shell 2 falls, and, as a consequence of this sudden and material reduction of the controlling or "dominant" pressure, the "servient" operating pressure in the primary shell becomes active and, by its expansion, forces the plunger 15 outwardly, past the pipe 3. The plunger 15 in its outward movement pulls the acid bottle past its center of gravity, and the latter completes its overturning movement by gravity, pulling away from the cap 19 and discharging its contents. The pressure thus developed forces a chemical stream through the pipe 12, shell 2 and distributing pipe. The rod 16 is provided with a packed head or equivalent device, as 21, which seals the opening 17, at the completion of the outward movement of the plunger.

The alternative embodiment shown in Fig. 2, departs from the embodiment shown in Fig. 1 in the construction and arrangement of the secondary shell and the appurtenant plunger mechanism therein. In the alternative embodiment, the secondary shell is indicated at 2^a and projects wholly within the shell 1. In the form of the invention shown in Fig. 1, the acid receptacle is overturned by a pulling action. In the present embodiment, the acid bottle is overturned by a pushing action and is so pivoted in the manner explained that it normally rests

against the shell 2^a. The latter has formed therein a barrel, as 10^a, which communicates directly with the pipe 12. The operating plunger, in the present instance, is shown at 15^a, and is provided with a stem, as 16^a, which projects axially and loosely through an opening, as 17^a, in the end wall of the shell 2^a. The plunger is provided with an opening 20^a and the charging pressure flows through this opening into the space between the plunger and the column of liquid in the pipe 12. The charging pressure also flows through the opening 17^a and into the shell. The stem 16^a is arranged to engage the upper portion of the acid bottle and to positively impart thereto the necessary initial unbalancing movement which causes the overturning of the bottle. The operative movement of the plunger is produced by the expansion of the fluid in the rear of the plunger consequent to the fall of the "dominant" pressure when a sprinkler head or its equivalent is opened. The plunger 15^a, in this instance, serves the function of the head 21 employed in the embodiment of Fig. 1, said plunger closing the opening 17^a and preventing the passage of gas from the shell 1 or of solution from the shell 2^a.

In the arrangement disclosed in Fig. 3, the machine is generally similar to the machine shown in Fig. 1. One modification resides in eliminating the hole in the piston and in its place, employing a by-pass pipe, as 22, which, as shown, connects the tank 1 and the distributing pipe 2 and is fitted with a diaphragm 23, having a "pin-hole" aperture 24. This arrangement provides for increasing the water level to a plane above the rod 16, and for consequently increasing the capacity without increasing the size of the tank. This relative height of the water line is also of advantage in case the chemicals used be of such nature that corrosion takes place above the water line, in which case the movable parts are submerged. The operation involves the basic principles described, the expansion of the air or gas in the secondary tank forcing a column of liquid against the piston and thereby producing an operative movement of the latter. In this arrangement the piston is of ordinary disk form; the opening 17 is of tapered form and the head 21 is conical in order to seat conformably in the opening when the piston has reached the limit of its outward movement.

Having fully described my invention, I claim:

1. In a chemical mixing fire extinguisher system, in combination, a system of piping, primary and secondary shells, the secondary shell being in direct communication with the piping system, means for putting equal pressure in the piping system and in both of the shells, chemical mixing means in the

5 primary shell and means normally restrained against operation by the normal pressure in the secondary shell and operable by the fluid in the primary shell upon a reduction of pressure in the secondary shell for causing the operation of the chemical mixing means.

10 2. In a fire extinguisher system, in combination, a system of piping, primary and secondary shells, the secondary shell being in direct communication with the piping system, means for putting equal pressure in the piping system and in the shells and means normally restrained against operation by the normal pressure in the secondary shell and operable by the fluid in the primary shell upon a reduction of pressure in the secondary shell for increasing the pressure in the primary shell.

15 20 3. In a fire extinguisher system, in combination, a system of piping, primary and secondary shells, the secondary shell being in direct communication with the piping system, means for putting equal pressure in the piping system and in the shells, the primary shell communicating with the system through the secondary shell and means normally restrained against operation by the normal pressure in the secondary shell and operable by the fluid in the primary shell upon a reduction of pressure in the secondary shell for establishing communication between the primary shell and the system and for increasing the pressure in the primary shell.

25 35 4. In a chemical mixing fire extinguisher system, in combination, a system of piping, primary and secondary shells, the secondary shell being in direct communication with the piping system, means for putting equal pressure in the piping system and in the shells, the primary shell communicating with the system through the secondary shell, an invertible acid bottle in the primary shell and a member movably mounted in the secondary shell and normally held by the fluid therein in position to shut off communication between the primary shell and the piping system and operable by the fluid in the primary shell, when the pressure in the secondary shell is reduced, to cause the overturning of the acid bottle and to establish communication between the primary shell and the secondary shell.

40 45 55 60 65 5. In a chemical mixing fire extinguisher system, in combination, a system of piping, primary and secondary shells, the secondary shell being in direct communication with the piping system, means for putting equal pressure in the piping system and in the shells, a pipe connection affording direct communication between the secondary shell and the primary shell, an invertible acid bottle in the primary shell, the secondary shell having a barrel communicating with the

70 pipe connection and having also an opening at one end thereof, and a plunger in the secondary shell and provided with a stem extending through said opening, said plunger being normally held in the secondary shell against the end of the barrel and being operable by the pressure of the fluid in the primary shell when the pressure in the secondary shell is reduced, to establish communication between said shells and to cause the overturning of the acid bottle.

75 80 85 90 95 6. In a chemical mixing fire extinguisher system, in combination, a system of piping, primary and secondary shells, the secondary shell being in direct communication with the piping system, means for putting equal pressure in the piping system and in the shells, a pipe connection affording direct communication between the secondary shell and the primary shell, an invertible acid bottle in the primary shell, the secondary shell having a barrel communicating with the pipe connection and having also an opening at one end thereof, a plunger in the secondary shell and provided with a stem extending through said opening, a loose fitting stopper closing said acid bottle and a chain connecting said stopper and said stem, said plunger being normally held against the end of the barrel and being operable by the pressure of the fluid in the primary shell when the pressure in the secondary shell is reduced, to establish communication between said shells and to overturn the acid bottle.

100 105 110 115 120 7. In a fire extinguisher system, in combination, a system of piping, primary and secondary shells, the secondary shell being in direct communication with the piping system, the system and the shells having pressure therein, means for maintaining such pressure normally equal to compensate for slight pressure variations and means normally restrained against operation by the normal pressure in the secondary shell and operable by the fluid in the primary shell upon a sudden and material reduction of pressure in the secondary shell for putting additional pressure in the system.

125 8. In a fire extinguisher system, in combination, a system of piping, primary and secondary shells, the secondary shell being in direct communication with the piping system, the system and the shells having pressure therein, means for maintaining such pressure normally equal to compensate for slight pressure variations, an acid bottle in the primary shell, and means normally restrained against operation by the normal pressure in the secondary shell and operable by the fluid in the primary shell upon a sudden and material reduction of pressure in the secondary shell for causing the discharge of the contents of the acid bottle in the primary shell.

130 9. In a fire extinguisher system, fire ex-

tinguisher agent supply means, a shell containing the supply means, a second shell communicating with the first shell, a piping system communicating with the second shell and provided with a distributing valve, means for putting fluid under pressure in the piping system and in both of the shells, means affording additional communication between the first shell and the piping system in order that slight variations of pressure in the latter may be equalized in the former without producing an operation of the system and means normally restrained from operation by the fluid in the second shell and operable by the fluid normally maintained in the first shell for producing the operation of the fire extinguisher agent supply means upon a material reduction of the pressure of the fluid in the piping system and the second shell, incident to the opening of the distributing valve.

10. In a fire extinguisher system, fire extinguisher agent supply means, a shell containing the supply means, a second shell communicating with the first shell, a piping system communicating with the second shell, means for putting fluid under equal pressure in the piping system and in both of the shells, and a slidably movable piston normally held in a position to interrupt the communication of the shells, the piston being moved by the pressure in the first shell upon a reduction of the pressure in the second shell to establish communication between the shells and being so related to the supply means as, upon its movement, to cause the operation of the supply means, the system having also means for equalizing the pressure in the first shell with that in the piping and in the second shell.

11. In a fire extinguisher system, fire extinguisher agent supply means, a shell containing the supply means, a second shell communicating with the first shell, a piping system communicating with the second shell, means for putting fluid under equal pressure in the piping system and in both of the shells and a movable mechanical element normally held in restraint by the fluid in the second shell and caused to operate by the fluid in the first shell to produce the operation of the supply means when the pressure in the second shell is suddenly and materially reduced.

12. In a fire extinguisher system, in combination, a system of piping, primary and secondary shells, the secondary shell being in direct communication with the piping system, means for putting equal pressure in the piping system and in the shells, fire extinguisher agent supply means in the primary shell, and means normally restrained against operation by the normal pressure in the secondary shell and operable

by the fluid in the primary shell upon a reduction of pressure in the secondary shell for causing the operation of the fire extinguisher agent supply means.

13. In a chemical mixing fire extinguisher system, in combination, a primary and a secondary shell, a distributing pipe communicating directly with the secondary shell, the latter communicating with the primary shell, a piston slidable axially of the secondary shell, an acid bottle in the primary shell, means whereby the piston in its operative movement causes the acid bottle to discharge its contents into the primary shell, a by-pass pipe connecting the primary shell and the distributing pipe, an apertured diaphragm in the by-pass pipe, and means for charging the distributing pipe, secondary shell, and primary shell with the elastic fluid under pressure.

14. In a dry pipe chemical mixing fire extinguisher system, a solution containing shell, a distributing pipe, a secondary shell, an acid bottle arranged to be discharged into the solution containing shell and an element movable axially of the secondary shell and in its movement providing for the discharge of the acid bottle, the distributing pipe being in open communication with the secondary shell on one side of the movable element in the normal position of the latter and in restricted communication with the secondary shell on the opposite side of said element.

15. In a dry pipe chemical mixing fire extinguisher system, a solution containing shell adapted to be partially filled with solution, and to have an air space above the solution, a distributing pipe normally containing air and through which the extinguishing fluid flows when the system is in operation, a secondary shell in open communication with the distributing pipe, an acid bottle arranged to discharge its contents into the solution containing shell, and a piston movable axially of the secondary shell under pneumatic pressure and in its axial movement providing for the discharging operation of the acid bottle, the piston having its opposite faces subject to the respective air pressures in the distributing pipe and in the solution containing shell, the solution containing shell and the distributing pipe having restricted communication with one another whereby the pressures at opposite sides of the piston are normally equal, the communication being of such degree that a rapid reduction of pressure at one side of the piston will result in the unbalancing of the pressure at the other side of the piston and in a consequent operative movement of the latter from its normal position.

16. In a chemical mixing fire extinguisher system, a solution containing shell and a dis-

tributing pipe leading therefrom, an acid bottle arranged to discharge its contents into the shell, a pressure operated plunger which governs the discharging operation of the acid bottle, a shell in which the plunger is movable and which communicates with the distributing pipe, the latter and the solution containing shell being adapted to contain an elastic fluid under pressure, and 10 a by-pass between the elastic fluid space of the solution containing shell and the dis-

tributing pipe to maintain the pressure in said shell and said pipe equal at all times except when the pressure in the pipe is suddenly vented.

15
